REFRIGERATOR CABINET

Robert R. Fink, Chicago, Ill., assignor to General
Electric Company, a corporation of New York

Filed Dec. 14, 1959, Ser. No. 58,645

Term of patent 14 years

(Cl. D67—3)

FIG. 1

Des. 191,242

PAGE 2

FIG.2

FIG. 3

FIG. 1 is a front elevational view of a refrigerator cabinet showing my new design.

FIG. 2 is a side elevational view thereof; and FIG. 3 is a front perspective view thereof. The rear is substantially plain.

What is claimed is:

The ornamental design for a refrigerator cabinet, substantially as shown and described.
